UNITED STATES PATENT OFFICE

157,087

STEREOSCOPE

Richard G. Reineman, Covina, Calif., assignor to
Fairchild Camera and Instrument Corporation,
Pasadena, Calif., a corporation of Delaware

Application October 25, 1948, Serial No. 149,292

Term of patent 14 years

(Cl. D57—1)

To all whom it may concern:

Be it known that I, Richard G. Reineman, a citizen of the United States, residing at Covina, in the county of Los Angeles and State of California, have invented a new, original, and ornamental Design for a Stereoscope, of which the following is a specification, reference being had to the accompanying drawing, forming part thereof, in which:

Fig. 1 is a perspective view of a stereoscope showing my new design with the supports and magnifying elements extended;

Fig. 2 is a top plan view thereof;

Fig. 3 is an end elevational view of the same;

Fig. 4 is a side elevational view with all of the extended elements retracted;

Fig. 5 is a bottom plan view of the same;

Fig. 6 is an end elevational view thereof; and

Fig. 7 is a side elevational view of the opposite side shown in Fig. 4.

I claim:

The ornamental design for a stereoscope, as shown and described.

RICHARD G. REINEMAN.
